UNITED STATES PATENT OFFICE.

SAMUEL B. H. VANCE, OF NEW YORK, N. Y.

CHANDELIER.

SPECIFICATION forming part of Letters Patent No. 245,894, dated August 16, 1881.

Application filed March 31, 1881. (Model.)

To all whom it may concern:

Be it known that I, SAMUEL B. H. VANCE, of New York city, New York, have invented certain new and useful Improvements in Chandeliers, of which the following is a specification.

My invention relates to drop-light chandeliers having fixed branching arms supporting stationary lights and a center slide or drop-tube supporting a drop-light.

10 The object of my invention is to improve the construction of the central stem or tubes of the chandelier which contain the gas-ducts supplying the fixed branches and the drop-tube, so that the gas will not only be supplied to the said parts by distinct and independent channels, but which will enable the several concentric tubes or sections of the stem to be put together and finished in a manner more convenient and simple than hitherto, and which 15 will also serve to prevent the exposure of the exterior of the drop-tube to gas-scented spaces or surfaces in the stem, as hereinafter fully set forth.

In the annexed drawings, Figure 1 presents a vertical section of such parts of a drop-light chandelier as embody my invention, the same being, of course, much shortened for illustration. Fig. 2 is a cross-section on xx , and Fig. 3 a plan of the top coupling.

20 The central stem of the chandelier is surmounted, as usual, by a coupling, a , which screws at the top to the gas-nipple projecting from the ceiling, or to a pipe extending therefrom, as will be understood. In a central opening in this coupling is screwed a slender central gas-tube, b , which extends downward through the center of the chandelier-stem, and terminates at a short distance below the branching arms, as shown. c indicates the drop-tube, 25 which slides telescopically over the gas-tube b , having a suitable form of stuffing-box, d , at its upper end to embrace the tube b gas-tight, while its lower extremity supports the drop-light, which is not shown.

30 Into the coupling a is screwed a larger tube, e , which incloses both the central gas-tube, b , and the drop-tube c , the latter of which is preferably square in cross-section, as seen in Fig. 2, and slides through a square opening 35 of snug fit in an ornamental cup, f , screwed

onto the end of the inclosing-tube e , as seen in Fig. 1.

In one former chandelier of this class the drop-tube moves gas-tight in its inclosing-tube in the manner of a piston, and the central gas-tube, b , is not used, while around the inclosing-tube has been placed a second tube of larger size, leaving an annular space between the two, through which the gas is supplied to the fixed arms. In my chandelier, however, 55 it will be seen that the drop-tube moves gas-tight on the center gas-tube, b , and moves loosely in the tube e , which simply incloses it. As this arrangement of tubes, however, has also been used before, it forms no claim of 60 mine. It will be seen, however, that in my construction the space between the drop-tube and its inclosing-tube e forms a free air-space, and a slot, g , extends through the top of the nipple into this annular air-space to admit the 65 metallic ribbon h , which extends from a spring-drum (not shown) fixed on the head of the chandelier, and connects to the top of the drop-tube in a manner now employed in chandeliers, so as to suspend or balance the drop-tube and its attachments at any position, as 70 will be readily understood. This slot or passage g thus renders the space in which the drop-tube moves open to the atmosphere at the top, and it is also open to the air at the 75 bottom through the loose-fitting screw-cap f , so that any slight leakage of gas into this space becomes rapidly diffused and carried off by the air-circulation thus allowed therethrough, thereby preventing any such accumulation as would tend to permanently scent the drop-tube and cause it to give out an unpleasant odor when drawn down; but this feature I do not here claim, broadly, as the same is shown in a previous patent issued to me 80 November 7, 1876.

Now, i indicates an annular coupling, which screws onto the inner coupling, a , and extends below it, and k indicate two semi-annular tubes of large diameter, which junction closely 85 together diametrically, as shown best in Fig. 2, and by dotted lines in Fig. 1, and encircle and inclose all the inner tubes of the chandelier, being screwed at the upper end into the annular coupling i , and at the lower end into 90 95 100

the hollow hub *l*, from which the branching arms *m* extend, as fully shown in Figs. 1 and 2. The upper end of the semi-annular tubes *k k* screw sufficiently far into the outer coupling *i*, so that their inner edges abut against the lower edge of the inner coupling, *a*, as shown in Fig. 1. After the semi-annular tubes are screwed into the position shown they are soldered in place by the blow-pipe, or by what is known as "sweating," so that the solder will follow or flow over all the fine capillary spaces or surface between the joints, thus making the connection firm and gas-tight without closing the narrow semicircular mouths of the annual tubes. It may now be seen on reference to Fig. 1 that the lower end of the semi-annular tubes *k k* opens into the hollow hub *l*, from which the branching arms *m* extend, while the upper end thereof opens into an annular space between the couplings *a* and *i*, into which oblique holes *n n* are bored from the central gas-passage of the coupling, through which holes the gas is admitted to the semi-annular tubes, and thence through the hollow hub *l* to the arms *m*, which support the stationary lights, in the usual manner.

It will thus be seen that by my invention the semi-annular tubes *k k*, in which the chief novelty lies, form the gas-passage to supply the fixed arms of the chandelier, and that this passage is complete in itself, and distinct from the central passage, *b*, which supplies the drop-tube; hence, as the outer tubes or ducts of the chandelier which supply the arms and inclose the inner tubes are by my invention made in sections or halves, it will be observed that the parts may be thus put together in a more quick and simple manner than is the case with continuous tubes. Furthermore, it will be seen that the tube *e*, which incloses the drop-tube, is by this construction kept from contact with the gas, both on its interior and exterior sides, except for a small portion where it passes

through the hub *l*, and that the drop-tube thus moves in a free air-space within said inclosing tube, as before described, so that the scenting of the exterior of the drop-tube is thus effectually obviated, which forms a most desirable advantage of this construction, as will be appreciated. 45

It should be mentioned that the hub *l* is, of course, soldered to the tube *e* where the latter projects therefrom, so as to render the connection firm and gas-tight, and that, furthermore, the solder fastening the lower end of the semi-annular tube is designed to run into and close the lower end of the slight space between the tube *e* and the semi-annular tubes *k k*, as at *r*, so as to prevent the gas rising between said tubes, and thus form a dead-air space between 60 the same, as will be understood. 50

It will be obvious that instead of making the divided tubes *k k* in two divisions, three or more may be used; but it is apparent that two semi-annular tubes or diametrical divisions are preferable. 55

What I claim is—

1. A drop-light chandelier having its stem constructed with semi or partially annual tubes *k k*, inclosing the inner tubes, and forming a distinct gas-duct to supply the fixed branches of the chandelier, substantially as herein set forth. 70

2. A drop-light chandelier having its stem composed of the central gas-tube, *b*, drop-tube *c*, sliding thereon, and third tube, *e*, inclosing the same and open to the air at top and bottom, with the semi-annular tubes *k k*, inclosing the latter and forming the gas-duct to supply the fixed arms of the chandelier, substantially 80 as shown and described. 75
